PORTABLE VACUUM CLEANER

Ernst Faber, Stuttgart, Germany

Application December 30, 1935, Serial No. 56,782
In Germany January 4, 1935

5 Claims. (Cl. 15—16)

In the known vacuum cleaners that run upon two rear side wheels and one central front wheel, which is usually oscillatable, the disadvantage is experienced that when the vacuum cleaner is standing upon a step it is very liable to roll down off the step accidentally, particularly if it receives a jerk by a pull on the suction tube.

The object of this invention is to remedy this defect in vacuum cleaners of the aforementioned or some similar construction, this result being obtained by fitting to the vacuum cleaner casing a locking appliance which enables the central running roller to be braked at will or prevented from rolling along the floor, and also, it may be, from swinging to one side, this latter feature being for the purpose of ensuring that the roller cannot escape from the action of the locking means. The braking of the roller prevents the vacuum cleaner from rolling down a step or an inclined surface, whereas when working on a level floor the locking device is put out of operation.

One form of construction of the invention is illustrated by way of example in the accompanying drawing, in which

25 Figure 1 shows a partial under-side view of a vacuum cleaner casing equipped with the locking appliance, and

Figure 2 shows the said casing in side elevation. Near the front or suction end of the vacuum cleaner casing *a* is mounted a central wheel or roller *c*, which is oscillatable about a vertical pivot *b*, and towards the rear end of the vacuum cleaner casing are provided two lateral running rollers or wheels *d*. Now according to the invention there is provided behind the front roller *c* a sliding bolt or locking bar *e*, which is displaceable in the longitudinal direction of the vacuum cleaner casing in a support *f* screwed to the latter, and is braked or held fast in its end positions 40 by a spring blade *g*. The drawing shows the sliding bar in its operative end position. Its inoperative position, at the other end of its travel, is shown in dot-and-dash lines in Figure 2. At its front end the locking bar is bent so far down that when slid forward it comes into frictional contact with the periphery of the roller *c*. The locking bar is brought into this position when the vacuum cleaner is standing upon a step, and then prevents the roller from turning, thereby preventing the vacuum cleaner from rolling downstairs, whereas in its normal position at the other end of its travel, for working upon a level floor, it permits the vacuum cleaner to move without hindrance.

55 In order to ensure that the roller cannot escape from the action of the locking bar by swinging sideways, lateral lugs *h* are provided at the

front end of the bar, which engage round the periphery of the roller.

What I claim is:—

1. In a portable vacuum cleaner, a casing, wheels on which the casing rests and moves, and a locking bar slidably supported on the under side of the casing and capable of being moved at will into and out of a position in which it engages one of the wheels and prevents it from revolving.

2. In a portable vacuum cleaner, a casing, wheels on which the casing rests and moves, one of the wheels being oscillatable about a vertical axis, a locking bar slidably supported on the under side of the casing, and lateral lugs at one end of the locking bar, the locking bar being capable of being moved at will into and out of a position in which it brakes the oscillatable wheel and the lugs engage round the periphery of the wheel and prevent it from swinging towards either side.

3. In a vacuum cleaner, a casing, wheels on which the casing rests and moves, one of the wheels swivelling about a vertical axis located in the central longitudinal vertical plane of the casing, longitudinal guiding means on the under side of the casing in the same vertical plane, and a locking bar slidable in the said guiding means with sufficient friction to hold it fast in any position into which it is adjusted, the locking bar being adapted in one position to engage with and 25 brake the swivelling wheel.

4. In a vacuum cleaner, a casing, wheels on which the casing rests and moves, one of the wheels swivelling about a vertical axis located in the central longitudinal plane of the casing, longitudinal guiding means on the under side of the casing in the same vertical plane, a locking bar slidable in the said guiding means, and resilient means for pressing the locking bar into engagement with its guiding means and thereby holding it fast by friction in any position into which it is adjusted, the locking bar being adapted in one position to engage with and brake the swivelling wheel.

5. In a vacuum cleaner, a casing, wheels on which the casing rests and moves, one of the wheels swivelling about a vertical axis, longitudinal guiding means on the under side of the casing in a vertical plane containing the said vertical swivelling axis, a locking bar slidable in the said guiding means, the locking bar being adapted in one position to engage with and brake the swivelling wheel, and lateral lugs on the locking bar adapted to prevent the wheel swivelling when it is braked.

ERNST FABER.
